UNITED STATES PATENT OFFICE.

GEORGE G. FLOYD, OF RIVERSIDE, ILLINOIS, ASSIGNOR TO WILLIAM H. MINER, OF CHAZY, NEW YORK.

PROCESS OF MANUFACTURING DRAFT-RIGGING YOKES.

Application filed July 24, 1919. Serial No. 313,097.

To all whom it may concern:

Be it known that I, GEORGE G. FLOYD, a citizen of the United States, residing at Riverside, in the county of Cook and State of Illinois, have invented a certain new and useful Improvement in Processes of Manufacturing Draft-Rigging Yokes, of which the following is a full, clear, concise, and exact description, reference being had to the accompanying drawings, forming a part of this specification.

This invention relates to improvements in process of manufacturing draft rigging yokes.

In certain types of railway draft riggings, it has been found advisable to employ yokes for operatively connecting the shock absorbing mechanism proper with the draw bar, which yokes will permit of a swinging or radial movement of the draw bar with respect to the shock absorbing mechanism proper. It is not new, broadly, to provide a so-called "pivotal yoke" but heretofore, such yokes have usually been manufactured in the form of castings entirely in order to obtain the proper pivotal connection between the head and strap.

As is well known, cast metal is not as efficient per weight of metal under tension as is wrought metal and consequently, it is desirable to provide a yoke in which the principal tension member is formed of wrought or rolled metal and the element which is directly connected to the coupler, formed of cast metal. It has also been found desirable not only to provide a pivotal connection between the so-called head and strap members, but in addition, to so arrange the pivotal connection that relatively longitudinal movement between the head and strap, as might occur in a buffing movement, be prevented.

It is also desirable that the head and strap be so assembled when manufactured and shipped for application, that they cannot be disassembled accidentally before application to the cars.

The object of my invention is to provide a simple, efficient and commercially practical process of manufacturing a draft rigging yoke composed of two elements, a cast head and a wrought or rolled yoke strap, possessing all of the desirable features above enumerated and free from the objections indicated.

In the drawings forming a part of this

specification, Figure 1 is a plan or layout of the strap part of the yoke, Figure 1 illustrating said strap as it is first formed. Fig. 2 is a side elevation of the strap in the form illustrated in Fig. 1. Fig. 3 is a side elevation of the strap as it appears in its final or finished form but disassembled from the yoke head. Fig. 4 illustrates the yoke strap as temporarily deformed or compressed, in order to permit its insertion within the yoke head and subsequent uniting therewith. Fig. 4 also indicates a portion of the head in section showing the manner in which the strap and head are assembled. Fig. 5 is a side elevation of a completed yoke made in accordance with my process. And Fig. 6 is a top plan view of the yoke shown in Fig. 5, a portion of the strap being broken away in order to accommodate the figure on the sheet of the drawing.

Before describing the process forming the subject matter of this application, I will first describe the completed article in order that a clearer idea may be obtained of the steps employed in the process. For this purpose, reference will first be made to Figs. 5 and 6.

The completed yoke, as shown, comprises two elements designated generally by the references A and B. The reference A is applied to what is known as the yoke head and the reference B to the part known as the strap. Said head A is preferably in the form of a malleable casting and has two side walls 10—10 and upper and lower transversely extending connecting walls 11—11, thus forming a head which is hollow and of substantially box-like or rectangular form. The side walls 10 are forwardly extended as indicated at 110 in Figs. 5 and 6, this being done in order to provide sufficient metal surrounding the usual coupler key slots 12—12, it being understood that a transversely extending key will be extended through said slots 12 and through a corresponding slot in the rear of the coupler, the butt of the coupler being disposed within the head A when the yoke and draw bar are assembled. In order to permit of swinging or radial movement between the head A and strap B, I make the forward edges of the upper and lower walls 11 concave as indicated at 13 in Fig. 6. It will be noted that these concave bearing edges 13 are quite extended and in fact, the maximum obtainable in a head of the width shown in the draw-

ing. The rear edges of the upper and lower walls 11 are left straight as indicated at 14. Preferably, the side walls 10 of the head are flared somewhat as apparent from inspection of Fig. 6 and also, to better accommodate the relative swinging movements of the strap and head, the latter is provided on the inner faces of the side walls thereof with beveled grooves 15—15 in alinement 10 with the upper and lower opposed portions of the arms of the strap B.

The strap B is of substantially U-shape having an upper arm 16, lower arm 17 and a rear connecting section 18. At their forward ends, the arms 16 and 17 are provided with enlarged heads indicated at 19—19, which may be said to be of T-form, that is, they are extended laterally beyond the side edges of the main body of the 20 strap arms 16 and 17. These T-heads 19 are also made substantially thicker than the thickness of the main portions of the strap as indicated at 20—20 in Fig. 5. This is for the purpose of obtaining greater 25 strength where the pulling load is applied to the strap and also to obtain a wider bearing on the rear convexly curved edges 21—21 of the T-heads which cooperate with the concave bearing edges 13 of the head A. The 30 arms 16 and 17 of the strap B are also formed with offsets indicated at 22—22 passing around the upper and lower walls 11—11 of the head A. This results in the formation of shoulders in the arms 16 and 35 17, said shoulders being indicated at 23—23 on the rear sides of the upper and lower walls 11 of the head A. Said shoulders 23 are preferably made convex as indicated at 40 24 in Fig. 6, so as to facilitate relative swinging movements between the head A and strap B.

As evident from an inspection of Figs. 5 and 6, the overall height of the strap B is substantially the same as the overall 45 height of the head A and consequently it is impossible to assemble the heads A and B by slipping the one over the other while the strap B is in its finished usable form.

In carrying out my process, I provide a 50 cast head A of the construction shown in the drawings and hereinbefore described. Such a cast head A is preferably in the form of a malleable casting and, of course, does not involve any molding or annealing 55 steps that are not well known.

In making the strap B, I first take a piece of wrought or rolled strap iron or steel of the proper width and thickness and necessary length. This strap I then forge or upset 60 while in the flat form to the design shown in Figs. 1 and 2 and indicated by the reference B³. In other words, the strap in its form indicated by the reference B³ has a main central section referenced 25 which is 65 perfectly flat and of the original form of

the stock material and at each end is offset and forged to provide T-heads 119 and offset portions 122. The T-heads 119 are thickened and formed with the convex bearing edges 121 and opposed shoulders formed 70 because of the offsets 122 are also convex as indicated at 124.

The next step in the formation of the strap is that of simple bending to a U-shape about suitable mandrels or forms so that 75 the strap assumes the condition indicated by the reference B² in Fig. 3. In this form, the strap is the same as in its completed form, both as to shape and size. During this step, the strap will not be subjected 80 to any severe or unusual strains since the bending occurs only at the corners indicated at 26—26 and no weakening of the metal will occur.

I next take the strap in its form indicated 85 by the reference B² and deform it or compress it in a vertical direction to the condition indicated in Fig. 4. In other words, the strap B² is compressed by applying pressure to the arms thereof at points well remote from the rear end of the strap so as to place bends 27—27 in the arms, said bends 27 being on a relatively long radius which will in nowise injure the metal. During this deforming step, the rear connecting section 90 of the strap will also be bent as indicated at 28 on a relatively long radius but without deforming the corner bends 26—26 that were previously in the strap of the form shown in Fig. 3. The deformation of the strap to the 95 form indicated by the reference B¹ decreases the vertical height of the strap, both at its rear end and at the forward free ends of the arms sufficiently to permit the insertion of the deformed strap B¹ longitudinally within 100 in the head A. This latter step then takes place merely by slipping the head A over the strap B¹ until the offset portions 122—122 of the strap come opposite the upper and lower walls 11—11 of the head A. 110 Thereupon, a suitable expanding tool in the form of a blunt wedge or other device will be inserted between the deformed arms of the strap and the latter spread until they are parallel and again in the finished or completed condition. Simultaneously with this spreading of the arms of the strap, the rear section 28 of the strap will tend to straighten and such straightening may be assisted by the suitable application of dies 115 or other tools thereto so as to leave the rear section of the strap straight, as shown in Figs. 3 and 5. The spreading of the arms of the strap as thus described will, of course, 120 result in the seating of the upper and lower walls 11—11 of the head A within the offsets 122 of the strap and thus leave the yoke in its final form ready for shipment and application without any danger of accidental disassembling or disconnection of the parts. 125

130

One of the important features of my process is in the elimination of the formation of any sharp bends in the strap, which sharp bends frequently result in permanent injury to the metal. By my process, I am also insured of retaining the proper bends in the corners at the rear end of the strap since these are formed at a time during the process of the manufacture of the strap when they can be accurately made. It is, of course, essential that the rear end of the strap be accurately formed because of the great tension to which the strap is subjected in actual service.

Although I have herein shown and described what I now consider the preferred manner of carrying out the process, I contemplate such changes and modifications as come within the scope of the claim appended hereto.

I claim:

The herein described process of manufacturing an assembled yoke having a hollow head and a substantially U-shaped strap which, when assembled in operative condition, have shouldered engagement with each

other, including: providing a hollow head having side, top and bottom walls; providing a substantially U-shaped strap of the finished size and form employed in the operative structure, each of the arms of the strap having spaced shoulders adapted for engagement with portions of said head when the two parts are operatively assembled; temporarily deforming said strap of the finished size and form to an overall height less than the distance between the top and bottom walls of the head to permit the head and strap being telescopically assembled; telescopically assembling the head and temporarily deformed strap; and finally reforming the strap to its finished size and operative form with the shoulders thereof in cooperative relation with the corresponding portions of the head.

In witness that I claim the foregoing I have hereunto subscribed my name this 3rd day of July 1919.

GEORGE G. FLOYD.
